UNITED STATES PATENT OFFICE.

CHARLES SMYTH, OF DAYTON, OHIO.

AIR GUN.

Application filed March 22, 1926. Serial No. 96,511.

This invention relates to an air gun and more particularly to an air gun designed for target shooting purposes at amusement resorts and similar places.

5 One object of the invention is to provide such an air gun which in appearance and manipulation will simulate an artillery rifle, or cannon, and which will discharge a projectile with sufficient force to cause the same to travel 10 with reasonable accuracy a distance sufficient for target shooting purposes.

A further object of the invention is to provide such a gun in which the source of power for discharging the projectile will not be 15 readily apparent, thus imparting to the gun an atmosphere of mystery which adds to its interest as an amusement device.

20 A further object of the invention is to provide such a gun with simple and efficient means for inserting the projectile therein and for controlling the discharge thereof.

25 A further object of the invention is to provide such a gun in which the means for inserting a projectile and for controlling the discharge thereof will be so controlled as to insure the proper sequence of operations, thus enabling the gun to be operated by a person unfamiliar therewith without danger of injury to the mechanism.

30 A further object of the invention is to provide such a gun with means for automatically determining the quantity of air admitted thereto for the purpose of discharging the projectile.

35 A further object of the invention is to provide such a gun with means whereby a plurality of projectiles will be successively presented in position for insertion into the barrel of the gun.

40 Other objects of the invention will appear as the mechanism is described in detail.

In the accompanying drawings Fig. 1 is a side elevation of an air gun embodying my invention; Fig. 2 is a transverse sectional view 45 taken on the line 2—2 of Fig. 1; Fig. 3 is a longitudinal section view showing the outer casing in section and showing the operating mechanism in side elevation and partly broken away; Fig. 4 is a longitudinal section view with the casing in section and showing the operating mechanism in plan view; Fig. 5 is a transverse sectional view taken on the line 5—5 of Fig. 4; Fig. 6 is a transverse sectional view taken on the line 55 6—6 of Fig. 4; Fig. 7 is a transverse sectional view taken on the line 7—7 of Fig. 3; Fig. 8

is a transverse sectional view taken on the line 8—8 of Fig. 4; Fig. 9 is a transverse sectional view taken on the line 9—9 of Fig. 4; Fig. 10 is a vertical sectional view taken centrally 60 of the rear portion of the operating mechanism; Fig. 11 is a sectional detail view of the breech mechanism for the gun; Fig. 12 is a detail view of the cut-off forming a part of the breech mechanism; Fig. 13 is a detail 65 view of the latch for retaining the air valve controlling device in the position to which it is moved when the projectile is inserted in the barrel; Fig. 14 is a plan view of the actuating device for the air valve; Fig. 15 is a 70 vertical sectional view of the air valve showing the actuating device therefor in elevation; Fig. 16 is a transverse sectional view on line 16—16 of Fig. 15; Fig. 17 is a top plan view partly broken away of the projectile 75 casing or magazine; Fig. 18 is a bottom plan view of the projectile casing; Fig. 19 is a longitudinal sectional view of the projectile casing taken on the line 19—19 of Fig. 17; Fig. 20 is a transverse sectional view of the projectile casing taken on the line 20—20 of Fig. 80 17; and Fig. 21 is a sectional detail view of the projectile.

In these drawings I have illustrated one embodiment of my invention and have shown 85 the operating mechanism as enclosed within an outer casing comprising front and rear portions 1 and 2 connected by a collar 3. The collar 3 has laterally extending trunnions 4 by means of which the casing, 1 and 2, is 90 mounted on a supporting frame 5, for movement about a horizontal axis. The supporting frame 5 in turn is mounted on a base 6 for movement about a vertical axis. The casing 1 and 2, and the mounting therefor are in general 95 appearance similar to an artillery rifle and the gun itself, that is, the casing 1 and 2 and the parts enclosed therein, is adjustable about both a horizontal and vertical axis to enable the same to be aimed at the target. 100

Mounted within the rear portion 1 of the outer casing is a supporting frame comprising transverse frame members 7, 8 and 9, which are preferably substantially disk-shaped to fit within the cylindrical casing 105 1, and an inner collar 10 arranged within the outer collar 3 and carrying a spider 11. The transverse frame members 7, 8 and 9 and the collar 10 are connected one to the other by tie rods 12 on which are mounted 110 spacing sleeves 13 to maintain the several transverse members rigidly in their properly

spaced positions. The barrel of the gun comprises an elongated tube 14 which is supported with its rear end in line with an opening 15 in the transverse frame member 8, which 5 opening constitutes a continuation of the barrel and forms a part of the breech thereof. The barrel or tube 14 extends forwardly through the frame member 9 and spider 11 and extends beyond the spider 11 to the forward end of the front portion 2 of the outer casing. Preferably the rear end of the barrel is supported in a boss 16 formed centrally of a housing 17, rigidly secured to the transverse frame member 8 and spaced 10 therefrom to form an air chamber 18. As here shown, the boss 16 is split longitudinally so that the end of the barrel may be inserted therein and the boss then clamped tightly about the same to secure it in position but 15 to permit of its ready removal.

The projectile is inserted in the barrel through the breech opening 15 in the frame member 8 and to this end means are provided for supporting the projectile in line 20 with the breech opening and in the path of a plunger 19, slidably mounted in the rear transverse frame member 7 and in the head 25 of the outer casing. As here shown, this plunger has at its rear end a handle 21 with 30 which are also connected guide rods 22 arranged above and below the plunger 19 and slidably mounted in the transverse frame members 7, 8 and 9. The projectiles may be placed in position for insertion into the barrel 35 and supported in that position in any suitable manner, either individually or in groups, but I prefer to utilize a projectile casing or magazine adapted to contain a plurality of projectiles and to so control 40 the position of this casing that the projectiles therein will be moved successively into line with the breech opening 15 for the barrel. As shown in Figs. 17, 18 and 19, this projectile casing 123 is flat in form and is provided 45 with a plurality of chambers or guide-ways 23 each adapted to receive a projectile 24, there being in the present instance six such chambers, thus enabling six projectiles to be placed in the gun at one time and then moved successively into loading position. The upper wall of the casing is preferably 50 continuous and each chamber may, if desired, be provided with a flat spring 25, or other suitable device, to frictionally engage 55 the projectile therein and hold the same against accidental displacement. The lower wall of the casing has a slot 26 extending longitudinally thereof for its full length and exposing portions of the lower surfaces 60 of the several projectiles which are within 65 the casing. The casing is, in the present instance, of such a width that it will fit snugly but slidably between the transverse frame members 7 and 8 and I have mounted between these frame members a supporting

plate 27 arranged in an inclined position beneath the breech opening 15, and the outer casing 1 has in its upper side a slot 28 through which the projectile casing may be introduced and in its lower side an opening 29 70 through which that casing may be removed. Mounted on the supporting plate 27 is a stop, such as a block 30, arranged to enter the slot 26 in the bottom wall of the projectile casing, when the latter is placed in position on 75 the supporting plate, and to be engaged by the lowermost projectile in the casing to limit the downward movement of the casing. The supporting plate 27 and the stop block 30 are so arranged with relation to the 80 breech opening 15 that the projectile which is in contact with the stop block will be supported in line with the breech opening and with the plunger 19 so that the forward movement of the plunger will cause it to engage 85 the rear end of the projectile, force the same through the breech opening and into the barrel 14 with its rear end lying beyond the air chamber 18. After the projectile has been inserted in the barrel the plunger is withdrawn to its normal position beyond the rear end of the projectile casing, thus releasing 90 that casing and permitting the same to move downwardly by gravity to bring the next projectile into contact with the stop 30. In 95 this manner the several projectiles in the casing the successively and automatically moved into loading position. The projectile itself may be of any suitable character but I have here shown it of an elongated 100 cylindrical shape with a tapered forward end so that it has much the appearance of a large caliber cartridge. Preferably the forward end of the projectile is weighted, as shown at 31, so as to cause the projectile to 105 travel in a substantially horizontal position with its tapered end forward.

After the projectile has been inserted in the barrel of the gun the breech opening 15 is closed and air under pressure admitted to 110 the air chamber 18 in sufficient quantities and of sufficient pressure to discharge the projectile from the barrel with a force sufficient to carry the same in an approximately straight line for a distance ample for target 115 shooting, usually from fifty to one hundred feet. The closing of the breech opening and the admission of air to the air chamber take place successively and are preferably controlled by a single operating device which so 120 controls the operations that the breech opening will necessarily be closed before air is admitted to the air chamber. As here shown, the breech opening is closed by means of a cut-off 32 in the form of an elongated plate or 125 valve which is pivotally mounted in the air chamber 18 for movement into and out of line with the breech opening 15. Preferably the cut-off has its contact face covered with yieldable material, as shown at 33, and is 130

acted upon by a spring 34 which presses this yieldable material firmly into contact with the forward face of the frame member 18 about the opening 15 and thus insures a tight closure of the breech opening. The cut-off is rigidly secured to a pivot pin 35 mounted in the wall of the housing 17 and having secured thereto an arm 36 with which is connected a spring 37 arranged to hold the cut-off normally out of line with the breech opening. As here shown, the arm 36 is arranged to engage the lower surface of the barrel 14 to limit the movement thereof. The pivot pin or stud shaft 35 lies in the path of a pin 39 carried by an arm 40 rigidly secured to a shaft 41 which is supported by the transverse frame members 7, 8 and 9 and extends beyond the head 20 of the outer casing 1, where it is provided with an operating handle 42. A second arm 43 rigidly secured to the shaft 41 is acted upon by a spring 44 to hold the shaft 41 and its connected parts in their normal positions. It will be apparent that when the shaft is rotated in a direction against the tension of the spring 44 the pin 39 will engage the arm 38 and thus move the pivot pin 35 and the cut-off 32 against the action of the spring 37, thereby moving the cut-off into a position to close the breech opening.

30 The air chamber 18 in the housing 17 may be connected with any suitable source of supply for air under pressure, such as an air compressor and, as here shown, the housing has a nipple 45 leading to the air chamber and connected by a flexible conduit 46 with one side of an air valve 47, the other side of which is connected by a flexible conduit 48 with a pipe 49 extending through one of the trunnions 4 of the collar 3 and thence downwardly through one of the side members of the frame 5 and then inwardly to the center of the frame and downwardly through the pivotal connection between the frame and the base or standard 6 and thence down through the standard to the ground, from whence it may be extended under ground or under any suitable cover to a source of air supply located at some distance from the gun. With this arrangement of the air supply the source of power for operating the gun is not readily apparent and this apparent lack of a source of power adds to the interest in the gun as an amusement device.

35 The valve 47, which controls the admission of air to the barrel of the gun, may be of any suitable character and may be operated in any suitable manner, but preferably the operating mechanism for the valve is of such a character that it will be moved to a retracted position when the projectile is inserted in the gun and will then be caused to operate the valve after the cut-off 32 has been closed.

40 As here shown, the valve casing has a transverse apertured partition 50 arranged between the conduits 46 and 48 and provided with a valve seat surrounding the aperture, and a valve member 51 is arranged to engage that seat to control the communication between the two conduits. The valve member has a guide stem 52 extending below the partition and arranged in the path of a plunger 53 slidably mounted in the lower part of the valve casing and so arranged that the upward movement of the plunger will cause it to engage the valve stem and move the valve member to its open position. By making the plunger 53 separate from the valve stem sufficient play between the two parts may be allowed to insure that the valve will always seat itself when released regardless of any variations in the length of the plunger. The lower end of the plunger 53 lies in the path of a pin 54 carried by the rear end of a lever 55 which is pivotally mounted at its forward end on a bracket 56, this bracket being supported by a bar or base plate 57 rigidly secured to the transverse frame members and collar 10 and forming a part of the main frame. The lever 55 is moved about its axis and vertical movement imparted to the pin 54 to cause the latter to control the position of the valve member 51 and this movement of the lever 55 is controlled by a cam plate 58 which is carried by a lever 59 pivotally mounted at its forward end on the upright flange of an angle bar 60 which is slidably mounted on the base plate 57. The length of the cam plate 58 is so proportioned with relation to the movement imparted to the angle bar 60 that when that bar is moved to the limit of its movement in either direction the cam 58 will have been carried entirely beyond the pin 54. At its forward end the cam plate 58 has its lower edge beveled, as shown at 61, and the upper edge of the cam is so arranged with relation to the pin 54 that when the angle bar or slide plate 50 is moved forwardly the beveled forward edge of the cam will engage the pin and ride over the same, thus moving the lever 59 upwardly and permitting the cam to pass the pin without imparting any movement thereto. At its rear end the cam 58 has its upper edge beveled, as shown at 62, and this beveled edge is so arranged with relation to the pin 54 that when the cam is moved rearwardly, from its foremost position, the beveled rear end of the cam will pass beneath the pin 54 and thus move the same upwardly and cause it to open the valve. The valve will be held in its open position as long as the pin remains in contact with the upper surface of the cam and thus the length of time that the valve remains open and the amount of air admitted to the barrel of the gun, is determined by the speed at which the cam 58 moves from one position to the other.

45 The slide plate 60 which carries the operating cam for the valve may be actuated in any suitable manner but, in the present instance, this plate is acted upon by a spring 130

which tends to move the same toward and hold the same normally in its rearmost position and means are provided whereby the operation of the plunger 19 to insert a projectile in the barrel of the gun will move this slide plate forwardly against the action of its spring and cause the same to be locked in that position. After the plunger has returned to its normal position the operation of the shaft 41 first closes the cut-off 32 and then releases the slide plate 60 for movement by its spring, this movement causing the cam to open the valve and admit air to the gun barrel. This may be accomplished in various ways. In the present instance, I have connected the slide bar at its rear end with a rod 62 which is slidably mounted in brackets 63 and 64 on the base plate 57. A spring 65 coiled about the rod 62 and confined between the bracket 63 and stop collar 66 on the rod tends to move the latter and the slide 60 rearwardly. The guide rods 22, connected with the handle 21 for the plunger 19, have secured thereto a cross head 67 which in turn is rigidly secured to a sleeve 68 slidably mounted on the barrel or tube 14. A spring 69 confined between a collar 70 on the end of the sleeve 68 and the spider 11 serves to return the sleeve and consequently the handle 21 and plunger 19 to their normal positions when the handle is released. A collar 72 secured to the lower guide rod 22 has a depending portion or lug 73 arranged to engage a finger 74 extending upwardly from the collar 66. The lug 73 is normally spaced such a distance from the finger 74 that it will not engage the finger until the plunger has partly completed its movement, thus causing less movement to be imparted to the controlling rod than is imparted to the plunger 19. Cooperating with a stop 75 on the rod 62 is a latch 76 which is pivotally mounted on the bracket 64, extends lengthwise of the rod 62 above the same and when unrestrained will be moved by gravity into contact with the rod. When the parts are in their normal positions the stop 75 will lie in the rear of the free end of the latch 76 and the forward movement of the rod 62 will move the stop 75 beyond the end of the latch which will ride over the same and then drop into the path thereof so as to prevent the rearward movement of the rod by the spring 65, the stop being so arranged on the rod 62 that when it is in operative engagement with the latch the valve actuating cam 58 will lie on the forward side of the pin 54. The latch 76 is connected by means of a link 77 with an arm 78 loosely mounted on the shaft 41, (see Figs. 7 and 13), so that the shaft may rotate in the hub of the arm. Rigidly secured to this shaft 41, adjacent to the arm 78, is a second arm 79 having a pin 80 arranged to engage the arm 78 when the shaft 41 is rotated and lift the arm 78 and the latch 76, thus releasing the controlling rod 62 for movement by the spring 65. It will be noted that the pin 80 of the latch actuating device is normally spaced a considerable distance from the adjacent edge of the arm 78. Consequently the shaft 41 is permitted to move a distance sufficient to insure the operation of the cut-off 32 before the controlling rod is released and the air valve opened by the rearward movement of that rod. As has been stated the amount of air admitted to the barrel of the gun is controlled by the length of time required for the valve actuating cam 58 to pass the pin 54. The movement of the rod 62 and consequently of the cam may be regulated in any suitable manner. As here shown, the rear end of the rod 62 is provided with a piston 81 which is mounted in an air cylinder or dash pot 82, the relief port of which is controlled by a screw 83 so that the escape of air therefrom may be regulated and the movement of the rod 62 timed accordingly. Means are also provided to insure that the plunger and its connected parts are moved to the full end of their movement in either direction thus insuring the proper positioning of all the parts. As here shown, a pawl 84 is pivotally mounted on the cross head 67 carried by the guide rod 22 and swings freely thereon. This pawl is so arranged that when the guide rods are moved forwardly it will engage a toothed rack 85 rigidly secured to the base plate 57 and will ride over that rack in an inclined position so that the rear end of the pawl will engage the successive teeth of the rack and prevent the rearward movement of the pawl and guide rods until the guide rods have been moved forward far enough to permit the pawl to clear the toothed rack and again assume a vertical position. When the guide rods are moved rearwardly through the action of the spring 69 the pawl will ride over the toothed rack in the opposite direction, thus preventing the forward movement of the guide rods and their connected parts until they have been moved to their rearmost positions.

Locking devices are provided to prevent the operation of the discharge controlling shaft 41 while the plunger 19 is in an advanced position and to prevent the advancement of the plunger 19 when the shaft 41 has been moved from its normal position. (See Figs. 3, 4 and 8.) Pivotally mounted on the transverse frame member 9 is an arm 86, the inner end of which is movable into and out of the path of a collar 87 rigidly secured to the sleeve 68. A spring 88 acts on this arm to hold the same normally out of the path of the collar 87 and in contact with a shoulder or cam 89 on the shaft 41. This shoulder 89 is so arranged that when the shaft is rotated in an operative direction it will force the arm 86 upwardly and into the path of the collar 87, thus preventing the forward movement of the sleeve 68 and the parts con-

nected therewith. Pivots mounted on the frame member 9 above the sleeve 68 is a second arm 90 the lower end of which is movable into and out of a position directly above and in the path of the arm 86. A spring 91 acts on the arm 90 to move the same into the path of the arm 86. Carried by the lower portion of the arm 90 is a finger 92 which overlaps the rear side of the collar 87 on the sleeve 68 and is so arranged that when that sleeve is moved to its rearmost position it will engage the finger and move the arm 90 out of the path of the arm 86. The shoulder or cam 89 which engages the lower edge of the arm 86 being rigidly secured to the shaft 41 it will be obvious that that shaft cannot be rotated unless the arm 86 is free to move upwardly and when this movement is prevented by the arm 90 the shaft 41 is positively locked against movement. A finger 93 on the shaft 41 contacts with one of the tie rods 12 to limit the movement of the shaft 41 in a reverse direction. I have also provided means for preventing the operation of the plunger 19 when there is no projectile case in position in the gun. To this end I have mounted in the frame members 8 and 9 a shaft 94, the rear end of which extends beneath the supporting plate 27 for the projectile case and has secured thereto an arm 95, the end portion of which is bent upwardly, as shown at 96 and adapted to extend through a slot 97 in the supporting plate into the path of the projectile case. Secured to the shaft 94, adjacent to the frame member 9, is a second arm 98 which is acted upon by a spring 99 which tends to move the shaft 94 in a direction to retain the end portion 96 of the arm 95 above the surface of the supporting plate 27. When the portion 96 of the arm 95 extends above the surface of the plate 27 the spring 99 will move the arm 98 into the path of the collar 87 on the sleeve 68 and it will thus prevent the forward movement of the sleeve and the plunger. When a projectile case is inserted in the gun the lower surface thereof will contact with the upturned end portion of the arm 95 and force the same downwardly below the surface of the supporting plate and this movement will also serve to carry the arm 98 out of the path of the collar 87 and thereby release the plunger for movement.

The operation of the mechanism will be readily understood from the foregoing description and it will be apparent that when the gun is to be used the projectile case containing one or more projectiles is inserted in the casing of the gun and the lowermost projectile therein is automatically centered with relation to the breech opening of the gun. The insertion of this casing having released the plunger 19 for operation the operator grasps the handle 21 and forces the plunger forward, thus forcing the projectile into the

barrel of the gun. The full stroke mechanism makes it necessary for the plunger to be moved forward its full distance and thus insures the proper positioning of the projectile in the barrel of the gun. This forward movement of the plunger also carries the valve controlling rod 62 to its foremost position in which position it is engaged by the latch 76 which retains it in its advanced position when the plunger has been released and returned to its retracted position by the spring 69. As soon as the plunger has been released the operating handle 42 of the shaft 41 is actuated, thus rotating the shaft 41 and causing the locking arm 86 to be moved into a position to hold the plunger against movement. The further movement of the shaft moves the cut-off 32 into a position to close the breech opening and after this has been accomplished the pin 80 of the arm 79 will engage the arm 78 and actuate the latch 76 to release the controlling rod 62 for movement by the spring 65. This movement of the rod carries the valve actuating cam beneath the pin 54 and opens the valve to admit air to the air chamber 18 and the barrel in the rear of the projectile. The air pressure is maintained during an interval determined by the adjusting screw 83 of the dash pot 82. The air thus admitted to the barrel will discharge the projectile from the barrel with sufficient force to carry it in a substantially straight line for a considerable distance.

While I have shown and described one embodiment of my invention I wish it to be understood that I do not desire to be limited to the details thereof as various modifications may occur to a person skilled in the art.

Having now fully described my invention what I claim as new and desire to secure by Letters Patent, is:

1. In an air gun, a main frame comprising a transverse frame member having an opening therethrough, a plate mounted on said frame member and having a hollow boss in line with said opening and having means for spacing a portion thereof from said frame member to form an air chamber, a barrel mounted in said hollow boss, a closure mounted in said air chamber for movement into and out of a position to close the opening in said frame member, means for actuating said closure, and means for introducing air under pressure into said air chamber.

2. In an air gun, a barrel having a breech opening through which a projectile may be inserted therein, means for supporting a projectile in line with said opening, a plunger to move said projectile through said opening into said barrel, means to close said breech opening after said projectile has been inserted in said barrel, a conduit to connect said barrel with a source of supply for air under pressure, a valve interposed in said conduit, a spring operated valve actuating device,

means controlled by the movement of said plunger to move said actuating device against the tension of its spring, a detent to hold said valve actuating device against movement by its spring, and means to move said detent into an inoperative position.

3. In an air gun, a barrel having a breech opening through which a projectile may be inserted therein, means for supporting a projectile in line with said opening, a plunger to move said projectile through said opening into said barrel, means to close said breech opening after said projectile has been inserted in said barrel, a detent to connect said barrel with a source of supply for air under pressure, a valve in said conduit, a spring operated valve actuating device, cooperating parts connected with said plunger and with said valve actuating device to cause the latter to be moved against the tension of its spring by the forward movement of said plunger, a detent to hold said valve actuating device against movement by its spring, and means to move said detent into an inoperative position.

4. In an air gun, a main frame, a barrel mounted in said main frame and having a breech opening through which a projectile may be inserted therein, means for supporting a projectile in line with said opening, a plunger to move said projectile through said opening into said barrel, guide rods connected with said plunger and slidably mounted in said main frame, a sleeve slidably mounted on said barrel, means for rigidly connecting said sleeve with said guide rods, a spring acting on said sleeve to resist the forward movement thereof, means to close said breech opening after a projectile has been inserted in said barrel, and means to admit air under pressure to said barrel after said opening has been closed.

5. In an air gun, a main frame, a barrel mounted in said main frame and having a breech opening through which a projectile may be inserted therein, means for supporting a projectile in line with said opening, a plunger to move said projectile through said opening into said barrel, guide rods connected with said plunger and slidably mounted in said main frame, a sleeve slidably mounted on said barrel, means for rigidly connecting said sleeve with said guide rods, a spring acting on said sleeve to resist the forward movement thereof, means to close said breech opening after a projectile has been inserted in said barrel, a detent to connect said barrel with a source of supply for air under pressure, a rod slidably mounted on said frame, a valve actuating member connected with said rod, a spring acting on said rod to move the same in one direction, cooperating parts carried by said rod and one of said guide rods to move said spring controlled rod against the action of said spring, a detent to hold

said spring controlled rod against movement by its spring, and means to move said detent into an inoperative position.

6. In an air gun, a main frame, a barrel mounted in said main frame and having a breech opening through which a projectile may be inserted therein, means for supporting a projectile in line with said opening, a plunger to move said projectile through said opening into said barrel, guide rods connected with said plunger and slidably mounted in said main frame, a sleeve slidably mounted on said barrel, means for rigidly connecting said sleeve with said guide rods, a spring acting on said sleeve to resist the forward movement thereof, means to close said breech opening after a projectile has been inserted in said barrel, a detent to connect said barrel with a source of supply for air under pressure, a rod slidably mounted on said frame, a valve actuating member connected with said rod, a spring acting on said rod to move the same in one direction, cooperating parts carried by said rod and one of said guide rods to move said spring controlled rod against the action of said spring, a detent to hold said spring controlled rod against movement by its spring, means to move said detent into an inoperative position, and adjustable means to regulate the movement of said rod by said spring.

7. In an air gun, a barrel having a breech opening through which a projectile may be inserted therein, means for supporting a projectile in line with said opening, a plunger to move said projectile through said opening into said barrel, a closure for said breech opening, a conduit to connect said barrel with a source of supply for air under pressure, a valve in said conduit, a spring operated device for actuating said valve, a part connected with said plunger to retract said valve actuating device against the action of its spring when a projectile is inserted in said barrel, a detent to retain said valve actuating device in its retracted position, and means for first actuating the closure for said breech opening and then actuating said detent to release said valve actuating device.

8. In an air gun, a barrel having a breech opening through which a projectile may be inserted therein, means for supporting a projectile in line with said opening, a plunger to move said projectile through said opening into said barrel, a closure for said breech opening, a conduit to connect said barrel with a source of supply for air under pressure, a valve in said conduit, a spring operated device for actuating said valve, a part connected with said plunger to retract said valve actuating device against the action of its spring when a projectile is inserted in said barrel, a detent to retain said valve actuating device in its retracted position, and a rotatable shaft operatively connected with

said closure for said breech opening and operatively connected with said latch, said connections being so arranged that the rotation of said shaft will first cause said closure to be moved to its closed position and will then move said detent to its inoperative position.

9. In an air gun, a barrel having a breech opening through which a projectile may be inserted therein, means for supporting a projectile in line with said opening, a plunger to move said projectile through said opening into said barrel, a closure for said breech opening, a conduit to connect said barrel with a source of supply for air under pressure, a valve in said conduit, a spring operated device for actuating said valve, a part connected with said plunger to retract said valve actuating device against the action of its spring when a projectile is inserted in said barrel, a detent to retain said valve actuating device in its retracted position, a rotatable shaft, an operative connection between said shaft and said closure, an arm loosely mounted on said shaft and connected with said detent, and a second arm rigidly secured to said shaft and having a part supported normally at a distance from the first mentioned arm and arranged to actuate said first mentioned arm after said shaft has been rotated a distance sufficient to operate said closure.

10. In an air gun, a barrel having a breech opening through which a projectile may be inserted therein, means for supporting a projectile in line with said opening, a plunger to move said projectile through said opening into said barrel, a closure for said breech opening, a conduit to connect said barrel with a source of supply for air under pressure, a valve in said conduit, a spring operated device for actuating said valve, a part connected with said plunger to retract said valve actuating device against the action of its spring when a projectile is inserted in said barrel, a detent to retain said valve actuating device in its retracted position, a rotatable shaft operatively connected with said closure and with said detent, and means to prevent the operation of said plunger when said shaft has been moved from its normal position.

11. In an air gun, a barrel having a breech opening through which a projectile may be inserted therein, means for supporting a projectile in line with said opening, a plunger to move said projectile through said opening into said barrel, a closure for said breech opening, a conduit to connect said barrel with a source of supply for air under pressure, a valve in said conduit, a spring operated device for actuating said valve, a part connected with said plunger to retract said valve actuating device against the action of its spring when a projectile is inserted in

said barrel, a detent to retain said valve actuating device in its retracted position, means to actuate said detent to release said valve actuating device, and means for preventing the operation of said releasing means when 70 said plunger has been moved from its normal position.

12. In an air gun, a barrel having a breech opening through which a projectile may be inserted therein, means for supporting a projectile in line with said opening, a plunger to move said projectile through said opening into said barrel, a closure for said breech opening, an air conduit connected with said barrel, a valve in said conduit, an actuating 75 device for said valve, a device having means to control the operation of said closure and of said valve actuating device, and a locking device to prevent the operation of said plunger when said controlling device has been 80 moved from its initial position.

13. In an air gun, a barrel having a breech opening through which a projectile may be inserted therein, means for supporting a projectile in line with said opening, a plunger to move said projectile through said opening into said barrel, a closure for said breech opening, an air conduit connected with said barrel, a valve in said conduit, an actuating 85 device for said valve, a device having means to control the operation of said closure and of said valve actuating device, and means to prevent the operation of said controlling device when said plunger has been moved from its initial position.

14. In an air gun, a barrel having a breech opening through which a projectile may be inserted therein, means for supporting a projectile in line with said opening, a plunger to move a projectile through said opening 105 into said barrel, a sleeve slidably mounted on said barrel and connected with said plunger, a spring acting on said sleeve to hold said plunger normally in its rearmost position, a closure for said breech opening, an air conduit connected with said barrel, a valve in said conduit, a valve actuating device, a shaft having rotatory movement to control the operation of said closure and said valve actuating device, a stop on said sleeve, a locking 110 arm mounted for movement into and out of the path of said stop, and means carried by said rotatable shaft to control the position of said arm.

15. In an air gun, a barrel having a breech opening through which a projectile may be inserted therein, means for supporting a projectile in line with said opening, a plunger to move a projectile through said opening 120 into said barrel, a sleeve slidably mounted 125 on said barrel and connected with said plunger, a spring acting on said sleeve to hold said plunger normally in its rearmost position, a closure for said breech opening, an air conduit connected with said barrel, a valve in 130

5 said conduit, a valve actuating device, a shaft having rotatory movement to control the operation of said closure and said valve actuating device, a stop on said sleeve, a locking arm mounted for movement into and out of the path of said stop, a lug rigidly secured to said shaft and arranged to engage said arm, and means controlled by the position of the stop on said sleeve to hold said pivoted 10 arm in contact with the projection on said shaft and thereby prevent the rotation of said shaft.

16. In an air gun, a barrel having a breech opening through which a projectile may be inserted therein, means for supporting a projectile in line with said opening, a plunger to move a projectile through said opening into said barrel, a sleeve slidably mounted on said barrel and connected with said plunger, a 20 spring acting on said sleeve to hold said plunger normally in its rearmost position, a closure for said breech opening, an air conduit connected with said barrel, a valve in said conduit, a valve actuating device, a shaft having 25 rotatory movement to control the operation of said closure and said valve actuating device, a stop on said sleeve, a locking arm mounted for movement into and out of the path of said stop, a lug rigidly secured to said 30 shaft and arranged to engage said arm, a second arm pivotally mounted for movement into and out of the path of the first mentioned arm, a finger carried by said second arm and so arranged with relation to the stop on said 35 sleeve that said second arm will be moved out of the path of the first mentioned arm when said plunger is in its fully retracted position, and a spring tending to move said second arm into the path of the first mentioned 40 arm, thereby holding the same in contact with the projection on said shaft and preventing the rotation of said shaft.

17. In an air gun, a barrel having a breech opening through which a projectile may be inserted therein, a casing adapted to contain a plurality of projectiles, means for movably supporting said casing adjacent to said breech opening, whereby said projectiles may be moved successively into line with said breech 50 opening, a plunger to move that projectile which is in line with said breech opening into said barrel, means to close said breech opening after a projectile has been inserted in said barrel, and means to admit air under pressure to said barrel after said opening has been closed.

18. In an air gun, a barrel having a breech opening through which a projectile may be inserted therein, an inclined supporting member arranged beneath said breech opening, a projectile case adapted to be slidably supported on said supporting member and having a slot on the lower side thereof, a stop on said supporting member arranged to extend 60 through said slot and engage the lowermost

projectile in said casing and support said projectile in line with said breech opening, a plunger to move said projectile through said opening into said barrel, means to close said breech opening after said projectile has 70 been inserted in said barrel, and means to admit air under pressure to said barrel after said opening has been closed.

19. In an air gun, a barrel having a breech opening through which a projectile may be inserted therein, an inclined supporting member arranged beneath said breech opening, a projectile case adapted to be slidably supported on said supporting member and having a slot on the lower side thereof, a stop on said supporting member arranged to extend through said slot and engage the lowermost projectile in said casing and support said projectile in line with said breech opening, a plunger to move said projectile through 80 said breech opening into said barrel, means to close said breech opening after said projectile has been inserted in said barrel, means to admit air under pressure to said barrel after said opening has been closed, means 90 for normally locking said plunger against movement, and means actuated by said projectile case when the latter is placed in operative position on said supporting member to move said locking means into a locking position.

20. In an air gun, a barrel having a breech opening through which a projectile may be inserted therein, an inclined supporting member arranged beneath said breech opening, a projectile case adapted to be slidably supported on said supporting member and having a slot on the lower side thereof, a stop on said supporting member arranged to extend through said slot and engage the lowermost projectile in said casing and support said projectile in line with said breech opening, a plunger to move said projectile through said opening into said barrel, means to close said breech opening after said projectile has been inserted in said barrel, means to admit air under pressure to said barrel after said opening has been closed, a sleeve slidably mounted on said barrel connected with said plunger, a spring acting on said sleeve to move said plunger to its retracted position, a stop on said sleeve, a shaft extending lengthwise of said sleeve, an arm rigidly secured to said shaft, a spring to move said arm into the path of said stop and lock said sleeve and said plunger against movement, a second arm connected with said shaft and having a part extending normally above the surface of said supporting member and arranged to be depressed by said projectile case when the latter is placed on said supporting member and to move the first mentioned locking arm into an inoperative position.

21. In an air gun, a barrel having a breech opening through which a projectile may be 130

- inserted therein, a supporting member arranged adjacent to said breech opening, a projectile case adapted to be slidably supported on said supporting member, means to position said projectile case on said supporting member with a projectile in line with said breech opening, a plunger to move said projectile through said breech opening into said barrel, means to close said breech opening after said projectile has been inserted in said barrel, means to admit air under pressure to said barrel after said breech opening has been closed, a device for locking said plunger against movement, and means actuated by said projectile case when the latter is placed in position on said supporting member to control the position of said locking device. 22. In an air gun, a barrel having a breech opening through which a projectile may be inserted therein, means for supporting a projectile in line with said opening, a plunger to move said projectile through said opening into said barrel, a closure for said breech opening, a conduit to connect said barrel with a source of supply for air under pressure, a valve in said conduit, a spring operated device for actuating said valve, a part connected with said plunger to retract said valve actuating device against the action of its spring when a projectile is inserted in said barrel, a detent to retain said valve actuating device in its retracted position, means for first actuating a closure for said breech opening and then actuating said detent to release said valve actuating device, and adjustable means to determine the time said valve shall remain open. 23. In an air gun, a barrel, means for inserting a projectile in said barrel, an air conduit leading to said barrel in the rear of said projectile, a valve interposed in said conduit and comprising a casing having a valve seat, a valve member arranged to be held in contact with said seat solely by air pressure, a plunger slidably mounted in said casing and arranged to engage said valve member and move the same from said seat, and means for actuating said plunger. 24. In an air gun, a barrel having a breech opening through which a projectile may be inserted therein, means for closing said breech opening, an air conduit leading to said barrel, a valve interposed in said conduit and comprising a casing having a valve seat, a valve member arranged to be held in contact with said seat by air pressure, a plunger slidably mounted in said casing and arranged to engage said valve member and move the same from said seat, a spring actuated device to operate said plunger, and a single device for controlling said breech closing means and said actuating device for said plunger. 25. In an air gun, a barrel having a breech opening, means for inserting a projectile in said barrel through said breech opening, a movable closure for said breech opening, an air conduit communicating with said barrel in the rear of said projectile, a valve in said conduit, and a device separate from said means for inserting the projectile to first move said closure to a position to close said breech opening and then open said air valve. 26. In an air gun, a barrel having a breech opening, means for inserting a projectile in said barrel through said breech opening, a movable closure for said breech opening, an air conduit communicating with said barrel in the rear of said projectile, a valve in said conduit, and a device separate from said means for inserting the projectile to first move said closure to a position to close said breech opening and then open said air valve and positively retain the same in its open position for a predetermined period of time. 27. In an air gun, a barrel having a breech opening, means for inserting a projectile in said barrel through said breech opening, a movable closure for said breech opening, an air conduit communicating with said barrel in the rear of said projectile, a valve in said conduit, a device separate from said means for inserting the projectile to first move said closure to a position to close said breech opening and then open said air valve and positively retain the same in its open position for a predetermined period of time, and means for varying the period of time during which said air valve is retained in its open position. 28. In an air gun, a barrel having a breech opening, means for inserting a projectile in said barrel through said breech opening, a cut-off separate from said projectile inserting means and movable into and out of a position to close said breech opening, means for actuating said cut-off, an air conduit communicating with said barrel in the rear of said projectile, a valve in said conduit, means for actuating said valve, and a device operable independently of the operation of said projectile inserting means to cause said cut-off actuating means and said valve actuating means to operate successively. 29. In an air gun, a barrel having a breech opening, means for inserting a projectile in said barrel through said breech opening, a cut-off separate from said projectile inserting means and movable into and out of a position to close said breech opening, means for actuating said cut-off, an air conduit communicating with said barrel in the rear of said projectile, a valve in said conduit, means for actuating said valve, a shaft separate from said projectile inserting means and operatively connected with said cut-off actuating means and said valve actuating means, and means for actuating said shaft.

30. In an air gun, a barrel having a breech opening, a device for inserting a projectile in said barrel through said opening, a cut-off movable into and out of a position to close said opening, an air conduit communicating with said barrel, a valve in said conduit, a spring actuated device for opening said valve, means controlled by said projectile inserting device to retract said valve opening device against the action of its spring, a detent to retain said device in its retracted position when said projectile inserting device is returned to its normal position, and a single device to control the movement of said cut-off and the position of said detent.

31. In an air gun, a barrel having a breech opening, a device for inserting a projectile in said barrel through said opening, a cut-off movable into and out of a position to close said opening, an air conduit communicating with said barrel, a valve in said conduit, a spring actuated device for opening said valve, means controlled by said projectile inserting device to retract said valve opening device against the action of its spring, a detent to retain said device in its retracted position when said projectile inserting device is returned to its normal position, and means to move said cut-off to its closed position and to move said detent to its inoperative position.

32. In an air gun, a barrel having a breech opening, a device for inserting a projectile in said barrel through said opening, a cut-off movable into and out of a position to close said opening, an air conduit communicating with said barrel, a valve in said conduit, a spring actuated device for opening said valve, means controlled by said projectile inserting device to retract said valve opening device against the action of its spring, a detent to retain said device in its retracted position when said projectile inserting device is returned to its normal position, means to move said cut-off to its closed position and to move said detent to its inoperative position, and means to prevent the movement of said valve opening device in a reverse direction until it has completed its movement in the direction in which it has been started.

33. In an air gun, a barrel having a breech opening, a device for inserting a projectile in said barrel through said opening, a cut-off movable into and out of a position to close said opening, an air conduit communicating with said barrel, a valve in said conduit, a spring actuated device for opening said valve, means controlled by said projectile inserting device to retract said valve opening device against the action of its spring, a detent to retain said device in its retracted position when said projectile inserting device is returned to its normal position, means to move said cut-off to its closed position and to move said detent to its inoperative position, and

means to retard the movement of said valve opening device by its spring and retain the same in operative relation to said valve for a predetermined period of time.

34. In an air gun, a barrel having a breech opening, an operable device for inserting a projectile in said barrel, a cut-off movable into and out of a position to close said breech opening, an air conduit communicating with said barrel, a valve in said conduit, a device separate from said projectile inserting device to control the operation of said valve, and means controlled by the position of said controlling device to prevent the operation of said projectile inserting device when said controlling device has been moved from its normal position.

35. In an air gun, a barrel having a breech opening, an operable device for inserting a projectile in said barrel, a cut-off movable into and out of a position to close said breech opening, an air conduit communicating with said barrel, a valve in said conduit, a device separate from said projectile inserting device to control the operation of said valve, and means controlled by the position of said projectile inserting device to prevent the operation of said controlling device when said projectile inserting device has been moved from its normal position.

36. In an air gun, a barrel having a breech opening, an operable device for inserting a projectile in said barrel, a cut-off movable into and out of a position to close said breech opening, an air conduit communicating with said barrel, a valve in said conduit, a shaft to control the operation of said cut-off and said valve, and means to automatically lock said shaft against operation when said projectile inserting device is moved from its normal position.

37. In an air gun, a barrel having a breech opening, an operable device for inserting a projectile in said barrel, a cut-off movable into and out of a position to close said breech opening, an air conduit communicating with said barrel, a valve in said conduit, a shaft to control the operation of said cut-off and said valve, and means to automatically lock said projectile inserting device against operation when said shaft is moved from its normal position.

38. In an air gun, a barrel having a breech opening, an operable device for inserting a projectile in said barrel, a cut-off movable into and out of a position to close said breech opening, an air conduit communicating with said barrel, a valve in said conduit, a stud operatively connected with said valve to control the opening and closing thereof, a slide bar, a lever pivotally mounted on said slide bar, a cam carried by said lever and so arranged that when one end of said cam is moved into engagement with said stud said lever will be moved about its axis to permit

said cam to pass said stud without actuating the same and when the other end of said cam is moved into engagement with said stud said cam will actuate said stud and cause the same to open said air valve, and means to actuate said slide bar.

39. In an air gun, a barrel having a breech opening, an operable device for inserting a projectile in said barrel, a cut-off movable into and out of a position to close said breech opening, an air conduit communicating with said barrel, a valve in said conduit, a stud operatively connected with said valve to control the opening and closing thereof, a slide bar, a lever pivotally mounted on said slide bar, a cam carried by said lever and so arranged that when one end of said cam is moved into engagement with said stud said lever will be moved about its axis to permit said cam to pass said stud without actuating the same and when the other end of said cam is moved into engagement with said stud said cam will actuate said stud and cause the same to open said air valve, a spring to move said slide bar and said cam in the last mentioned direction, means actuated by said projectile inserting device to move said slide bar against the action of said spring, a detent to hold said bar against movement by said spring, and means to move said detent to an inoperative position.

40. In an air gun, a barrel having a breech opening, an operable device for inserting a projectile in said barrel, a cut-off movable into and out of a position to close said breech opening, an air conduit communicating with said barrel, a valve in said conduit comprising a casing and a valve member movably mounted in said casing, a plunger mounted in said casing to control the position of said valve member, a stud movably mounted in line with said plunger, a slide bar mounted adjacent to said stud, a lever pivotally mounted on said slide bar, an elongated cam carried by said lever and having one end shaped to ride over said stud and having its other end shaped to pass beneath said stud and cause the latter to actuate said plunger, and means for actuating said slide bar.

50 41: In an air gun, a barrel having a breech opening, an operable device for inserting a projectile in said barrel, a cut-off movable into and out of a position to close said breech opening, an air conduit communicating with said barrel, a valve in said conduit comprising a casing and a valve member movably mounted in said casing, a plunger mounted in said casing to control the position of said valve member, a stud movably mounted in line with said plunger, a slide bar mounted adjacent to said stud, a lever pivotally mounted on said slide bar, an elongated arm carried by said lever and having one end shaped to ride over said stud and having its other end shaped to pass beneath said stud and

cause the latter to actuate said plunger, means for actuating said slide bar, and adjustable means for regulating the movement of said slide bar.

42. In an air gun, a frame, a housing mounted on said frame and constituting an air chamber, a barrel having its rear end supported in one wall of said housing and communicating with said chamber, the opposite wall of said housing having an opening in line with said barrel, means for inserting a projectile in said barrel through said opening, a closure mounted within said housing for movement into and out of a position to close said opening, means for introducing air under pressure into said chamber, whereby said closure will be pressed against said wall about said opening, and means for actuating said closure and for controlling the admission of air to said chamber.

43. In an air gun, a supporting structure, a barrel carried by said supporting structure and having a breech opening through which a projectile may be inserted therein, a movable projectile supporting device adapted to carry a plurality of projectiles, means to support said device in different positions on said supporting structure to align different projectiles with said breech opening, means to move a projectile from said device through said breech opening into said barrel, means to close said breech opening after said projectile has been inserted in said barrel, and means to admit air under pressure to said barrel after said breech opening has been closed.

44. In an air gun, a barrel, means for inserting a projectile in said barrel, an air conduit leading to said barrel in the rear of said projectile, a valve interposed in said conduit and comprising a casing having a valve seat, a valve member arranged to be held in contact with said seat solely by air pressure, a plunger slidably mounted in said casing, and arranged to engage said valve member and move the same from said seat, and an actuating device for said plunger having means to hold said valve in said open position for a predetermined length of time.

45. In an air gun, a barrel having a breech opening through which a projectile may be inserted therein, means for closing said breech opening after said projectile has been inserted, an air conduit communicating with said barrel in the rear of said projectile, a valve to control the passage of air through said conduit, a spring actuated controlling device to open said valve, and means to retard the movement of said spring actuated device to determine the length of time said valve shall remain open.

46. In an air gun, a barrel having a breech opening through which a projectile may be inserted therein, means for closing said breech opening after said projectile has been inserted, an air conduit communicating with

- said barrel in the rear of said projectile, a valve to control the passage of air through said conduit, a device to control the opening and closing of said valve, actuating mechanism for said controlling device, and means for controlling the movement of said valve controlling device by said actuating mechanism to cause said valve to remain open for a predetermined period of time.
47. In an air gun, a barrel having a breech opening through which a projectile may be inserted therein, means for closing said breech opening after said projectile has been inserted, an air conduit communicating with said barrel in the rear of said projectile, a valve to control the passage of air through said conduit, a valve controlling device having means for retaining said valve in its open position during a predetermined movement of said device, and means for controlling the speed at which said controlling device moves.
48. In an air gun, a barrel having a breech opening through which a projectile may be inserted therein, means for closing said breech opening after said projectile has been inserted, an air conduit communicating with said barrel in the rear of said projectile, a valve to control the passage of air through said conduit, a member connected with said valve, a controlling device having a part of predetermined length to engage said member, move said valve to its open position and retain said valve in its open position as long as said part remains in engagement with said member, and means for moving said part at a predetermined speed.
49. In an air gun, a barrel having a breech opening through which a projectile may be inserted therein, means for closing said breech opening after said projectile has been inserted, an air conduit communicating with said barrel in the rear of said projectile, a valve to control the passage of air through said conduit, a valve controlling device having a part movable in two directions, and means controlled by said part to cause said valve to be opened when said part moves in one direction only.
50. In an air gun, a barrel having a breech opening through which a projectile may be inserted therein, a device for inserting a projectile in said barrel, means for closing said breech opening after a projectile has been inserted in said barrel, an air conduit communicating with said barrel in the rear of said projectile, a valve in said conduit, an actuating device comprising a part to engage said valve, and means controlled separately from said projectile inserting device to cause said part of said actuating device to engage and open said valve and to retain said part in engagement with said valve for a predetermined period of time.
51. In an air gun, a barrel having a breech opening through which a projectile may be inserted therein, a device for inserting a projectile in said barrel, means for closing said breech opening after a projectile has been inserted in said barrel, an air conduit communicating with said barrel in the rear of said projectile, a valve in said conduit, an actuating device comprising a part to engage said valve, means controlled by said projectile inserting device to move said part of said actuating device to a position preliminary to the operation of said valve, and means controlled separately from said projectile inserting device to cause said part to engage and open said valve and retain said part in engagement with said valve for a predetermined period of time.
52. In an air gun, a barrel having a breech opening through which a projectile may be inserted therein, means for closing said opening after a projectile has been inserted, an air conduit leading to said barrel in the rear of said projectile, a valve in said conduit, an actuating device for said valve comprising a part movable in one direction without opening said valve, and adapted to open said valve when moved in the other direction, means for controlling the movement of said part in the last mentioned direction to cause said valve to be retained in said open position for a predetermined interval, and means to prevent the movement of said part in said last mentioned direction until it has completed its movement in the first mentioned direction.

In testimony whereof, I affix my signature hereto.

CHARLES SMYTH.
